UNITED STATES PATENT OFFICE.

JAMES MACMARTIN, OF ALBANY, NEW YORK.

COMPOSITE TIE FOR RAILWAYS.

SPECIFICATION forming part of Letters Patent No. 790,373, dated May 23, 1905.

Application filed August 3, 1904. Serial No. 219,373.

To all whom it may concern:

Be it known that I, JAMES MACMARTIN, a citizen of the United States, and a resident of Albany, State of New York, have invented 5 new and useful Improvements in Composite Ties for Railways, of which the following is a specification.

This invention relates to composite ties for supporting and securing rails in place on road-beds of railways; and it consists in the novel devices and parts and the novel combinations and arrangements of the same hereinafter described, and set forth in the claims.

The objects of this invention are to produce 15 a composite tie made sectional for convenience of handling and combining in these sectional parts a concrete anchoring part; a metal part embedded in the concrete part and adapted to be suitably connected with a coacting similar metal part in a duplicate section; means for securely connecting said metal coacting parts; rail-blocks of wood secured to the concrete anchoring parts and adapted to receive and hold with spikes for holding with 25 rails.

Other purposes and advantages will be clearly understood by the following description when taken in connection with the accompanying drawings, in two sheets, forming 30 a part of this specification, in which—

Figure 1 is a plan view of my invention, showing a series of this improved tie and rails secured therewith. Fig. 2 is a longitudinal section of the composite tie. Fig. 3 is a transverse section taken at dotted lines 1 in Fig. 1. Fig. 4 is a longitudinal section of the wood block. Fig. 5 is an end view of the same. Fig. 6 is a side elevation of the concrete anchoring-block and incased channel-bars and wood-block coupling-bolts. Fig. 7 is an end view of the same. Fig. 8 is a plan view of the same. Fig. 9 is a side view of one side plate of a coupler and a section of the same. Fig. 10 is a channel-bar employed 40 inside the main channel-bars, as shown in Fig. 3. Fig. 11 is an end view and a section of a thimble between the side plates of a coupler.

Fig. 12 is a view of a coupler-bolt and its nut. Fig. 13 is a side elevation showing a modification of the concrete block and seat 50 for locating the wood block. Fig. 14 is an end view of the same, and Fig. 15 is a plan of the same.

Similar marks of reference refer to similar parts throughout the several views.

This composite tie is made sectional for convenience of shipment and handling in laying the same. As each half or section of these composite ties is a duplicate of the other half or coacting section, a description of the one 60 section or half part of the tie will suffice for that of the other.

In the drawings, A is a block of any suitable wood, as southern pine, oak, or other wood employed for ties in railway construction. This block is of suitable proportion and preferably of length about eighteen inches, in width about six inches, and in thickness about six inches. These dimensions, or any of them, may be greater or less according to 65 the service required from the railway to be constructed. For heavy traffic this block A may be made with a width of eight or ten inches, while for light traffic a depth of five inches with a width of six inches may suffice. 70 This block A is provided with vertical perforations *a a* for receiving coupling-bolts *b b*, which are about twelve inches, more or less, apart from centers. These perforations are made central in larger perforations *a' a'* sunken 75 to a depth adapted to receive a washer and a nut of thickness corresponding with the bolt *b*.

B is a concrete block for service as an anchoring-block for the tie and is preferably produced by molding for exact duplication 80 of the same, and preferably is made of a standard cement, sand, or finely-broken stone, and small stone in proportion of one part of cement, two parts of sand or finely-broken stone, and four parts of one-half inch or less 85 of broken stone. These proportions of said substances may be varied as may be found to be advantageous. This block B is made with suitable dimensions as to length, width, and

thickness and with exterior form for adapting it to hold with the ballast of the road-bed and from an endwise shifting in either direction, and also for preventing the wood block A, 5 by means of side-guard portion b', from being moved outward by the outward thrust of the wheels against the inner side of the rails when on curves, and thereby prevent a spreading of rails. At present I prefer to 10 produce this concrete anchoring-block for general use about three feet long, or more or less, as may be found to be advantageous, and with a width about corresponding with that of the wood block and with a depth cor- 15 responding with that of the latter. Intermediate of these blocks is a coupling device C for coaction with a coupling-bar D, which co- 20 acts with a similar coupling-bar of a duplicate concrete anchoring-block. This cou- 25 pling-bar D consists of a pair of channel-bars d d, made with a length sufficient for extending longitudinally through said block to within a short distance of the outer end of the same and inward to a further distance, so 30 as to terminate at a point equal to half the width of the track between the rails, as the gage of the track may require. These channel-bars d d are of equal length and preferably are about three inches, more or less, in 35 width, with flanges d about one inch and one-half, more or less, as may be found to be ad- 40 vantageous. E E are registering pins passed through perforations e e, which register in said channel-bars d d and receive pins E E, 45 which preferably are of round rod about three-quarters of an inch, or more or less, in diameter. These perforations e e preferably are a little larger in diameter than the pins E for allowance of longitudinal contraction 50 of said channel-bars in cold weather in relation to the concrete block B, and they serve as a means for preventing the concrete block from shifting longitudinally in either direc- 55 tion in relation to said coupling device C. 60 Vertical perforations c' c', Fig. 2, of like diameter as perforations a a are provided in the block B, in alinement with the line of middle of width of said block, and also in alinement with perforations a a in the wood 65 block A, so that said perforations a a may register with perforations c' c' and conjointly serve as bolt-holes for receiving the vertical coupling-bolts F F for holding the wood block A securely fixed on the concrete block 70 B. These coupling-bolts F F have their heads f, same figure, on their lower ends and against washer f', which washer has bearing against the lower side flanges d' d' of the channel-bars d d of this coupling device D, 75 as shown in Figs. 2 and 3. The inner ex- 80 tended portions d' d' of the channel-bars d d terminate at the middle of the track, whatever its gage may be, and these extended portions d' d' are provided with like perfora-

tions g, which register in each extension 65 with those of the other.

The coupling device C consists of two plates c c, of greater thickness than the channel-bars d d for insuring both their tensile strength and stiffness. Between the plates c c, made 70 with registering perforations c², are arranged short tubular pieces c² c², Figs. 1, 2, and 11, in number corresponding with the number of perforations in the extension portions d² d² of both pair of channel-bars, as shown in 75 Figs. 1 and 2. This coupling device C, comprising duplicate side plates c c, Fig. 9, with their registering perforations c³ c³ and tubular pieces c² c², Fig. 11, is placed in between the extended portions d² d² of the pairs of 80 channel-bars provided with each pair of concrete blocks when being laid ready for being coupled together by bolts c' c', as shown in Figs. 2 and 12.

When this composite tie is to be laid, two 85 duplicate sections, Figs. 1 and 2, are coupled together by coupling device C, above described and as shown in the drawings, and the wood blocks A will be placed on the concrete blocks with a side thereof against the guard b', with 90 the perforations a a receiving the coupling-bolts b, fixed in the concrete blocks, when the nuts b' of said bolts will be screwed down tight in the large perforations provided to receive the said nuts, as shown in Figs. 2 and 4. 95 The rails may now be laid on the wood blocks, as required by the gage-measure, and are secured in place by spikes G G, as shown in Figs. 1, 2, and 3. When the road-bed has been prepared and has received its ballast, 100 whether of sand or gravel, the concrete blocks will be anchored therein from moving in either direction and will support the wood blocks wholly above the soil liable to become wet, so that said blocks will generally remain dry 105 and be preserved in best condition for service for a much longer time than when subjected to periods of alternate dryness and saturation, as ties are generally.

In this composite tie the coupling devices 110 are in alinement and are held from shifting in relation to the concrete blocks and not liable to become elongated because of absence of bends and offsets in the length of the bars which connect said concrete blocks.

In Figs. 13, 14, and 15 the concrete block is shown to have its corners slightly rounded and its sides and end slightly inclined and the seat for locating the wood block slightly sunken, so that the coupling-bolts b may be 115 entirely relieved from lateral strain. These modifications of exterior form of the concrete block may be employed or omitted, as preferred, without changing the functions and purposes of the parts of this composite tie.

These wood blocks may be produced cheaply with a saving of much valuable timber to the public.

Having described my invention, what I claim, and desire to secure by Letters Patent, is—

1. In a sectional composite tie, the combination with a concrete block of proportions described, provided on its upper side with a seat and projected guard for locating a wood tie-block, of a coupling device consisting of two parallel channel-bars arranged longitudinally and in part interior in said block and provided with registering perforations and placed at a suitable distance apart, of metal registering pins in the perforations in said bars for locating said channel-bars within said concrete block.

2. In a sectional composite tie, the combination with a concrete block of proportions described, provided on its upper side with a seat and a projected side guard for locating a wood tie-block, of a coupling device consisting of two parallel channel-bars arranged longitudinally and in part interior in said block, and provided with registering perforations placed at a suitable distance apart; metal pins for locating said bars in said block and holding them from longitudinally shifting; vertical coupling-bolts in the said concrete blocks and between said channel-bars, holding with the lower side of the same, and extended upward above the seat for locating a wood tie-block.

3. In a sectional composite tie, the combination with a concrete block described, coupling devices consisting of parallel channel-bars placed at suitable distances apart and extended through said block and from near the outer end of the same part to the middle of length of the sectional tie of registering pins through registering perforations in said bars and holding with the substance of said block, registering perforations in the extended portion of said channel-bars adapted to register with perforations in a coupling device adapted to connect the said extended ends with the extended end portions of a similar coupling device of a duplicate section of a composite tie.

4. In a sectional composite tie, the combination with two coupling devices comprising each two parallel channel-bars set at like suitable distances apart and provided with like registering perforations and adapted to stiffen and hold with duplicate concrete blocks when interior in the same; and horizontal pins through said registering perforations, of a coupler consisting of two plates, having perforations registering with the other registering perforations in said channel-bars and adapted to be received against the inner sides of said bars, tubular pieces between said plates at said registered perforations and coupling-bolts for clamping the contiguous end portions of the channel-bars against said coupler-plates.

5. In a sectional composite tie, the combi-

nation with two duplicate concrete blocks described, provided on their upper sides with means for locating a pair of wood tie-blocks, of two pairs of channel-bars each pair being a duplicate of the other pair, register pins in similar registering perforations for holding with the duplicate concrete blocks, vertical coupling-bolts fixed in the two concrete blocks and holding with the lower flange edges of both the channel-bars in each of the two blocks, and means for rigidly connecting the inner portions of the two pairs of channel-bars.

6. In a sectional composite tie, the combination with the wood tie-block described, for support of the rail and for holding the base thereof from moving in relation to the tie and provided with vertical perforations, at equal distances from the point of middle of length of said block, for receiving coupling-bolts and with larger perforations for receiving the nuts of said bolts; of a concrete block provided on its upper side with a seat and an upward projected side guard for locating said wood block; a longitudinal interior metal coupling device holding with the substance of the concrete block and stiffening the same; coupling-bolts holding with the lower edges of said metal coupling devices and projected upward through the said block and into the vertical perforations provided in the wood block and secured.

7. In a sectional composite tie, the combination with a wood tie-block, with perforations described, provided with bolt-holes at equal distances from the point of middle of said block and the concrete block for service as a base anchoring device to said wood block, and of construction adapted to locate the said block for receiving a rail, of a coupling device formed by two longitudinal parallel bars at suitable distances apart interior in said concrete block and adapted to be coupled with a similar coupling device, coupling-bolts between said bars and having their lower ends holding with the lower edges of the same and extended upward through the substance of the concrete block and through the wood block and secured.

8. In a composite tie, the combination with two pairs of equal longitudinal channel-bars in alignment and connected at the middle of the aggregated length of said bars by a coupling device rigidly fixed between the inner end portions of the two pairs of channel-bars, means for securing said bars from shifting longitudinally in either direction in relation to each other in said pairs, vertical coupling-bolts between the bars of each pair and holding with the lower edges of the same, and extended upward, of two concrete blocks each incasing the outer end portions of a pair of said channel-bars and incasing the vertical coupling-bolts and also the means employed for preventing a longitudinal shifting of said

bars, and two wood blocks of proportions described seated on the seats and against a projected side of each concrete block and secured thereto by said coupling-bolts; whereby two parallel railway-rails may be secured to said wood blocks by spikes, at the same time the wood blocks are securely held from moving

in relation to each other by the anchoring of the concrete blocks in the ballast material of the road-bed.

JAMES MACMARTIN.
